(57)

CLAIM

The ornamental design for a jewelry cleaner, as shown and described.

DESCRIPTION

FIG. 1 is a perspective view of a jewelry cleaner according to our new design;

FIG. 2 is a right elevation view thereof;

FIG. 3 is a rear elevation view thereof;

FIG. 4 is a left side elevation view thereof;

FIG. 5 is a front elevation view thereof;

FIG. 6 is a top plan view thereof;

FIG. 7 is a cross section view taken at line 7-7 of FIG. 6; and,

FIG. 8 is a bottom plan view of the jewelry cleaner of FIG. 1.

The broken lines depict portions of the jewelry cleaner that form no part of the claimed design.
